(57) **CLAIM**

The ornamental design for an intervertebral body fusion implant device, as shown and described.

DESCRIPTION

FIG. 1 is a left-side frontal top perspective view of an intervertebral body infusion implant device showing our new design;

FIG. 2 is a right side bottom rear perspective view thereof; FIG. 3 is a front view of the intervertebral body fusion implant device of FIG. 1;

FIG. 4 is a rear view of the intervertebral body fusion implant device of FIG. 1;

FIG. 5 is a left side view of the intervertebral body fusion implant device of FIG. 1, a right side view of the intervertebral body fusion implant device being a mirror image thereof; and,

FIG. 6 is a top view of the intervertebral body fusion implant device of FIG. 1, a bottom view of the intervertebral body fusion implant device being a mirror image thereof.
